DISPLAY CARD FOR SUNGLASSES OR THE LIKE

William G. Pacelli, Leominster, and Albert C. Petitto,
Hudson, Mass., assignors to Foster Grant Co., Inc.,
Leominster, Mass., a corporation of Delaware

Filed Nov. 24, 1958, Ser. No. 53,518

Term of patent 14 years

(Cl. D80—5)

The back, not shown, is substantially plain.

We claim:

The ornamental design for a display card for sunglasses or the like, substantially as shown and described.
